CONTAINER

James W. Chase, Neenah, Wis., assignor to Marathon Paper Mills Company, Rothschild, Wis., a corporation of Wisconsin

Application January 6, 1941, Serial No. 373,371

2 Claims. (Cl. 229—17)

This invention relates to a spout construction for containers. More specifically the invention relates to containers formed of cardboard and the like adapted for the transportation and dispensing of liquids, such as milk, of the type disclosed in Patent No. 2,218,670, October 22, 1940.

The purpose of the present invention is to provide a discharge opening having a spout adjacent thereto to facilitate pouring the contents from the container. In the previous constructions employed hitherto, as in the aforementioned Patent No. 2,218,670, it was found difficult to pour the contents without spilling. The present invention overcomes this difficulty by providing a spout portion which is formed from a tab portion integral with the container without involving the use of additional materials or increasing the cost of manufacture.

The invention is applicable to paper containers of various types and is susceptible of different uses. The embodiments disclosed in the following specification are set forth by way of example only for illustrating the inventive concept.

In the drawings:

Figure 1 is a perspective view of a completed container, the pouring opening being closed.

Figure 2 is a fragmental enlarged perspective view of the container showing the pouring opening uncovered.

Figure 3 is a similar view showing the outer tab folded to form a pouring spout.

Figure 4 is a sectional view taken on lines 4—4 of Figure 1.

Figure 5 is a plan view of the blank from which the container shown in Figure 1 is formed.

Figure 6 is a perspective view of a further modification of a completed container, the pouring opening being closed.

Figure 7 is a fragmental enlarged perspective view of the container showing the pouring opening uncovered.

Figure 8 is a similar view showing the outer tab folded to form a pouring spout.

Figure 9 is a plan view of the blank from which the container shown in Figure 6 is formed, and

Figure 10 is a view showing in plan a portion of the inner face of the blank.

Referring to the drawings, Figures 1 to 5, the container is made from a blank, as shown in Figure 5, suitably cut and scored to provide side wall panels 20, 31, 32 and 33 and glue panel 34. The side wall panels are provided with bottom end panels 35, 36, 37 and 38 respectively and

upper panels 39, 90, 91 and 92. Panels 39 and 91 are cut at their free edges so as to have a U-shaped contour indicated by numerals 93 and 94. When these panels are folded over into abutting relation as shown in Figure 4, the cut out portions form a rectangular opening through which the contents can be poured. Panel 92 is provided with a tongue portion 36 formed by a U-shaped cut line 11 which is hinged on line 10. Panel 90 is provided with an outwardly hingeable tab portion 1 which is formed by cut score lines 5, 7 and 6. The tab 1 is adapted to be hinged along score line 2. U-shaped cut lines 3 and 4 provide leg portions 50 and 51 which are hinged to the tab along lines 40 and 41. A portion 8 is cut out in order to permit grasping of the free edge of the tab 1 in order to hinge same outwardly.

In forming the carton from the blank, the walls are set up in right angular relation and glue panel 34 is glued to the inner face of panel 30. The bottom flaps 35 and 37 are then folded inwardly and flaps 36 and 38 are folded thereover in overlapping relation and glued together. Upper panels 39 and 91 are then folded inwardly. Panel 92 is then folded thereover and then panel 90 is folded over and adhered to panel 92 by suitable adhesive 10', except that no adhesive is applied adjacent the dispensing opening as indicated by numeral 29'. The container may be waterproofed with paraffin wax or other suitable composition, being coated inside and outside.

In using the container, the tab 1 is grasped adjacent the opening 8 and pulled outwardly to the position indicated in Figure 2. Portions 23 and 25 of the tab are then folded along score lines 9 and 10 to form a spout as shown in Figure 3. At the same time the leg portions 50 and 51 will be folded into position so as to lock against the free edges 5 and 6 of the receptacle thereby firmly retaining the spout in position. The tongue portion 36 being glued to tab 1 will also be bent outwardly thereby providing an opening in the receptacle for pouring the contents therefrom.

A further modification of the container construction is illustrated in Figures 6 to 10 where-in the container is similar to the construction illustrated in Figure 1. Leg portions 50 and 51 formed by U-shaped cut lines 3 and 4 extending below the hinge line 2 are hinged respectively along lines 40 and 41 to the body of the tab. In opening this container, the tab 1 is first pulled outwardly as shown in Figure 7. Portions 23 and 25 are then folded along score lines 9 and 10

to form a spout as shown in Figure 8 and the leg portions 50 and 51 are at the same time positioned into locking engagement with the corresponding free edges 5 and 6 thereby insuring retention of the pouring spout during pouring of the contents in the container.

I claim:

1. A container for use in the storage, transportation and dispensing of pourable materials, said container being fabricated of a plurality of flat angularly disposed marginally interconnected panels and being stiff and self-supporting, one wall thereof being cut or scored to provide a displaceable tab integrally connected to the wall by an uncut portion which constitutes a hinge line about which the tab may be swung outwardly to uncover a pouring opening, said tab being provided with spaced score lines intersecting said hinge line and a pair of spaced parallel slits extending from each end of the hinge line, and a transverse slit joining the extremities of each pair of slits to provide leg portions at each end of said hinge line, said tab when hinged outwardly on said hinge line and folded along said spaced score lines forming a spout portion and said leg portions folded at right angles to said spout portion and the ends thereof defined by said transverse slits engaged in abutting contact

with a cut portion of said wall for retaining the spout portion in position.

2. A container for use in the storage, transportation and dispensing of pourable materials, said container being fabricated of a plurality of flat angularly disposed marginally interconnected panels and being stiff and self-supporting, one wall thereof being cut or scored to provide a displaceable tab integrally connected to the wall by an uncut portion which constitutes a hinge line about which the tab may be swung outwardly to uncover a pouring opening, said tab being provided with spaced score lines intersecting said hinge line, said score lines extending from said hinge line in convergent relation, and a pair of spaced parallel slits extending from each end of the hinge line, and a transverse slit joining the extremities of each pair of slits to provide leg portions at each end of said hinge line, said tab when hinged outwardly on said hinge line and folded along said spaced score lines forming a spout portion and said leg portions folded at right angles to said spout portion and the ends thereof defined by said transverse slits engaged in abutting contact with a cut portion of said wall for retaining the spout portion in position.

JAMES W. CHASE.
